US0D1074662S

(12) **United States Design Patent** (10) **Patent No.:** **US D1,074,662 S**
(45) **Date of Patent:** **** May 13, 2025**

(54) **LOCK HOUSING**

(71) Applicant: **Binder GmbH**, Tuttlingen (DE)

(72) Inventors: **Ante Urtic**, Moenchweiler (DE);
Ahmet Arabul, Tuttlingen (DE)

(73) Assignee: **Binder GmbH**, Tuttlingen (DE)

(**) Term: **15 Years**

(21) Appl. No.: **29/854,390**

(22) Filed: **Sep. 23, 2022**

(30) **Foreign Application Priority Data**

Mar. 24, 2022 (EM) 008916613-0002

(51) **LOC (15) Cl.** **08-07**

(52) **U.S. Cl.**

USPC **D8/330**; D14/299

(58) **Field of Classification Search**

USPC ... D14/299, 240, 358, 300, 496, 314, 238.1;

(74) Attorney, Agent, or Firm — Akerman LLP; Peter A. Chiabotti; David J. Fernandez-Fidalgo

(57) **CLAIM**

The ornamental design for a lock housing as shown and described.

DESCRIPTION

FIG. 1 is a top view of the lock housing showing the new design;

FIG. 2 is a perspective view thereof;

FIG. 3 is a rear view thereof;

FIG. 4 is a side view thereof;

FIG. 5 is another side view thereof;

FIG. 6 is a bottom view thereof; and,

FIG. 7 is a front view thereof.

The portions shown in broken lines form no part of the claimed design.

1 Claim, 7 Drawing Sheets
